(57) **CLAIM**

The ornamental design for a control device, as shown and described.

DESCRIPTION

FIG. 1 is a first perspective view of a first embodiment of the control device showing our new design;

FIG. 2 is a second perspective view thereof, showing an inner tabular wall in an upward extended position;

FIG. 3 is a third perspective view thereof, showing a universal serial bus (USB) port with its cover open;

FIG. 4 is a top plan view thereof, showing the control device in use;

FIG. 5 is a bottom plan view thereof;

FIG. 6 is a first side view thereof, showing the inner tabular wall in an upward extended position;

FIG. 7 is a second side view thereof, showing the inner tabular wall in an upward extended position;

FIG. 8 is a sectional view thereof, showing the inner tabular wall in an upward extended position taken along line 8-8 in FIG. 5;

FIG. 9 is a first perspective view of a second embodiment of the control device;

FIG. 10 is a second perspective view thereof, showing the inner tabular wall in an upward extended position and the USB port cover open;

FIG. 11 is a top plan view thereof, showing the control device;

FIG. 12 is a bottom plan view thereof;

FIG. 13 is a first side view thereof;

FIG. 14 is a second side view thereof;

FIG. 15 is a left side view thereof;

FIG. 16 is a right side view thereof;

FIG. 17 is a third side view thereof, showing the inner tabular wall in an upward extended position;

FIG. 18 is a fourth side view thereof, showing the inner tabular wall in an upward extended position the USB port cover open;

FIG. 19 is a left side view thereof, showing the inner tabular wall in an upward extended position the USB port cover open;

FIG. 20 is a right side view thereof, showing the inner tabular wall in an upward extended position the USB port cover open; and,

FIG. 21 is a sectional view thereof, showing the inner tabular wall in an upward extended position taken along line 21-21 in FIG. 12.

In the drawings, the broken lines depict a portion of the control device, which form no part of the claim.
